UNITED STATES PATENT OFFICE

CHARLES K. STROBEL, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

DEVICE FOR OPERATING ON FLAT ARTICLES

Application filed March 20, 1930. Serial No. 437,623.

My invention relates to devices for operating on flat articles, and has for an object the provision of a novel and improved device for rubbing a limited portion of the surface 5 of an article in disk form.

I will describe one form of device embodying my invention, and will then point out the novel features thereof in the claim.

In the accompanying drawing, Fig. 1 is a 10 vertical sectional view showing one form of device embodying my invention with the parts in the positions which they occupy when the device is operating on an article. Fig. 2 is a top plan view of an article which 15 has been operated on by the device illustrated in Fig. 1.

Similar reference characters refer to similar parts in both views.

Devices embodying my invention are particularly suitable for, although in no way limited to, use in the manufacture of electrical rectifiers of the type disclosed and claimed in Letters Patent of the United States, No. 1,640,335, granted to Lars O. 20 Grondahl on August 23, 1927. In at least one form of rectifier of this type, rectifying elements consisting of metallic blanks, such as perforated disks or washers of copper or iron are treated to form a coating of a compound 25 of the metal, such as an oxide or iodide, on one side thereof. After the blanks have been thus treated, it is desirable to rub finely divided low resistance electrical conducting material, such as powdered petroleum coke, into the coated surface of the blanks. This operation is usually performed 30 by placing the blanks with the coated side up on a piece of suitable gripping material, such as emery cloth, and applying a rotating member, provided with a friction ring of suitable material, to the coated surface after the coated surface has been sprinkled with the powdered material which it is desired to rub into this surface. During this operation, 35 it is important that none of the powdered material be rubbed into the blanks adjacent the edges of the oxidized surface where it might be undesirable during subsequent stages in the preparation of the completed rectifier, and it is therefore desirable that a

narrow ring of the surface of the blanks adjacent each edge should not be rubbed. It sometimes happens, however, that if the coated surface of a blank is unusually rough, the blank starts spinning when the friction ring 55 is brought into engagement with this surface, and as a result, the powdered material is applied to more than the desired portion of the surface of the blank. The purpose of the present invention is primarily to provide 60 a device for rubbing the powdered material into the desired portion of the surface of the blanks in such manner that the blanks cannot spin during this operation, thereby eliminating 65 spoilage of blanks in manufacture and providing a superior product. It is to be understood, however, that devices embodying my invention, and one form of which I will now describe, are not limited to this use but are suitable for operating on the surface 70 of any kind of a flat article when similar results are to be attained.

Referring now to the drawing, one form of device embodying my invention comprises 75 a tapered shank 3 which is adapted for insertion in any suitable machine by means of which the device may be both rotated and reciprocated, such for example, as any of the well known forms of drill presses. Secured by means of screws 2 to a circular flange 3^a 80 formed on the lower end of the shank 3 is a cylindrical member 1, the upper and lower ends of which are provided, respectively, with two axially disposed cylindrical openings 4 and 5, which openings are separated 85 from each other by a partition 6. A bolt 7 extends with considerable clearance through an opening 6^a in the partition 6, and is fastened by means of a nut 7^a to two cones 8 and 9 which are located on opposite sides of 90 the partition 6 in the openings 4 and 5, respectively, and which are adapted to rotate freely with respect to the member 1 on ball bearings 10. Attached to the lower end of the bolt 7, and fitting freely in the cylindrical opening 5, is a hollow cylindrical member 11. 95 A plunger 12 extends with some clearance into the lower end of the cylindrical member 11, and is attached at its upper end to one end of a compression spring 13, the other end of 100

which is secured to the member 11. The lower end of the plunger 12 carries a gripping member 14 of suitable material such as fibre, rubber, micarta, etc., which will not injure the coating of a rectifier blank when the gripping member is forced into engagement with the surface of the blank by the spring 13 as will be explained more fully hereinafter. A ring 15 of suitable material, such as wood, is fastened to the lower end of the member 1 in any suitable manner, as by screws 16, and glued or otherwise secured to this ring is a friction ring 17 of rubber or other suitable material.

The parts are so proportioned that when the device is not engaging the surface of an article, the plunger 12 is forced downwardly by the spring 13 to a point where the gripping member 14 extends below the lower side of the friction ring 17. It will be apparent, therefore, that when the rotating device is moved into engagement with an article whose surface is to be rubbed, such for example, as the rectifier blank 18 shown in the drawing, the gripping member 14 comes into contact with the surface of the blank before the friction ring 17, thereby forcing plunger 12 upwardly and compressing spring 13. Since the cylindrical member 11 which supports the plunger 12 is free to rotate with respect to the member 1, it follows that when the friction ring 17 is rubbing the surface of a blank, the gripping member 14 remains stationary and applies pressure to the blank, thereby holding the blank firmly against its supporting plate 19 during the rubbing operation and hence preventing the blank from spinning.

As pointed out hereinbefore, it is important that a narrow ring adjacent each edge of the blank should not be rubbed. In Fig. 2, the shaded area 18^a indicates approximately the area that should be rubbed. It will be apparent that by making the friction ring 17 the proper size to engage this area of the blank only the desired area will be rubbed.

Although I have herein shown and described only one form of device embodying my invention, it is understood that various changes and modifications may be made therein within the scope of the appended claim without departing from the spirit and scope of my invention.

Having thus described my invention, what I claim is:

A device for rubbing the surface of a disk, comprising a rotatable shank, a first cylindrical member secured to said shank and provided in its upper and lower ends respectively with two cylindrical axially disposed openings separated by a partition having a hole extending therethrough, two cones located in said openings on opposite sides of said partition and adapted to rotate freely on ball bearings, a bolt extending through the hole in said partition with clearance and secured

to said cones, a second hollow cylindrical member fitting freely in the lower one of said openings and secured to said bolt, a compression spring in said second cylindrical member secured at one end to said second cylindrical member, a plunger extending into said second cylindrical member and secured at its upper end to the free end of said spring, a gripping member secured to the lower end of said plunger, and a friction ring secured to said first member, the parts being so proportioned that if said device is moved into engagement with said disk said gripping member will engage said disk and compress said spring before said friction ring engages said disk for preventing said disk from spinning while said friction ring is engaging said disk.

In testimony whereof I affix my signature.

CHARLES K. STROBEL.
